(57) **CLAIM**

The ornamental design for a one-piece hook for retaining scooters and skateboards, as shown and described.

DESCRIPTION

FIG. 1 is a perspective view of the one-piece hook for retaining scooters and skateboards, showing my new design;

FIG. 2 is a front elevational view thereof;

FIG. 3 is a rear elevational view thereof;

FIG. 4 is a side elevational view thereof, the other side being a mirror image;

FIG. 5 is a top plan view thereof; and,

FIG. 6 is a bottom plan view thereof.
